(74) Attorney, Agent, or Firm — Quinn IP Law

(57) CLAIM

The ornamental design for a dispensing cap, as shown and described.

DESCRIPTION

FIG. 1 is a front perspective view of a dispensing cap showing the claimed design;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a rear perspective view thereof.

The broken lines in the figures show portions of the dispensing cap and environment that form no part of the claimed design.

The trademark "L" logos located on the dispensing cap are a trademark of Legacy Shave, LLC.

The logo shown in the drawings, and forming part of the claim, is a registered trademark of Legacy Shave LLC.

1 Claim, 8 Drawing Sheets
